UNITED STATES PATENT OFFICE

2,063,418

CABINET AIR-CONDITIONER

Frank A. Whiteley, Minneapolis, Minn.

Application January 9, 1933, Serial No. 650,773
Renewed August 8, 1935

14 Claims. (Cl. 261—11)

My invention relates to cabinet air-conditioners, and has for its object to condition air in enclosed spaces, such for example as in a chamber formed above and in connection with the mattress of the bed or in a single room.

This application is in many respects a continuation of application Serial Number 624,469, filed on July 25, 1932 now Patent 1,971,631 dated Aug. 28, 1934.

It is the object of my invention to provide within a cabinet, either portable or built into the wall of a house, self-contained means therein for moving air through a tortuous passage formed within the cabinet and for providing a spray of water in most parts of said passage subject to said moving air, together with a mechanically refrigerated member in the bottom of the cabinet for contacting with the water to cool the same. It is a further object of my invention to form such a mechanically refrigerated member with an outer shell of cast metal entirely sealed from within so that the pipes which carry the refrigerating fluid will at no place be exposed to the currents of air being conditioned.

It is a further object of my invention to provide within the cabinet a tank for the water with improved means for easily filling said tank and also with means for permitting air to enter the tank noiselessly as water is withdrawn therefrom. It is a further object of my invention to provide novel means for delivering the air to the room or chamber to provide a novel arrangement of pump and blower operated by a single motor, to provide means for delivering both a coarse and a fine spray, to provide thermostatic means for regulating the temperature of the air as delivered, and to provide novel forms of scrubbers or devices for removing free water from the air before its delivery.

The full objects and advantages of my invention will appear in connection with the detailed description thereof, and its novel features are particularly pointed out in the claims.

In the drawings, illustrating preferred applications of my invention,—

Fig. 1 illustrates a sectional elevation of the cabinet air-conditioner as applied to a bed. Fig. 2 is a perspective detail showing a means of withdrawing the spraying member for cleaning the spray nozzles. Fig. 3 is a detail plan view of the top of the water supply tank. Fig. 4 is a sectional view on line 4—4 of Fig. 3. Fig. 5 is a detail sectional view on line 5—5 of Fig. 3. Fig. 6 is a sectional view of a bed and parts carried by

the air-cooling chamber applied thereto. Fig. 7 is a transverse sectional view on line 7—7 of Fig. 1. Fig. 8 is a sectional view on line 8—8 of Fig. 1 viewed in the direction of the arrows. Fig. 9 is a longitudinal sectional view of the air-conditioning cabinet adapted for use in a room independently of a bed. Fig. 10 is a sectional view on line 10—10 of Fig. 9 viewed in the direction of the arrows. Fig. 11 is a sectional view on line 11—11 of Fig. 9 viewed in the direction of the arrows. Fig. 12 is a fragmentary plan view of the secondary bottom wall of the cabinet shown in Fig. 9, on line 12—12 of Fig. 9.

A casing of considerable height, width and length, in practice about the length of a standard mattress, has the top wall 10, outside end walls 11 and 12, side walls 13 and 14 and a sloping bottom wall 15 which discharges at its lower end into a well or sump 16. Upon the bottom wall 15 rests a heat exchange member 17 connected by means of pipes 18, 19 with a refrigerating compressor indicated diagrammatically at 20 which may be located in an attic room, basement or other convenient place, the pipes 18, 19 passing to it through a partition wall as indicated at 21 in Fig. 1. The member 17 will in practice comprise a cast tube 22, Fig. 7, with fin plates 23 integrally cast therewith and adapted to rest upon the bottom 15 but cut away as indicated at 24 to provide a continuous channel down the bottom wall 15 for permitting the water falling from sprayers after it has passed over the fins 23 and the body 22 of the refrigerating member to run down said bottom wall 15 and discharge into the water chamber 25 of the well 16. Partition members 26 are attached to or in contact with top wall 10 of Fig. 9 or a horizontal partition 27 forming a passageway 28 between it and top member 10, as in Fig. 1. Other partition members 29 are secured to upstanding fin members 30 on the refrigerating member 17, as shown in Figs. 1, 7, and 9. As indicated at 31, the partition members 26 stop short of the refrigerating member 17 so as to leave passages under them, and the partition members 29 correspondingly fall short of reaching the top member 10 or the horizontal partition member 27, as indicated at 32 in Figs. 1 and 9, whereby an elongated tortuous passageway 33, as in Fig. 1, and 34 as in Fig. 9, is provided. At an end of the cabinet, next to the end wall 12, and between it and a vertical partition 35 is formed a chamber 36 in the bottom of which is the reservoir 25 for water. Above this reservoir and supported by a parti-

tion 37 is a water tank 38 of any suitable size. A neck 39 extends through the partition 37 and is provided with a nozzle 40 which dips well below the waterline 41 in reservoir 25, and which 5 is adapted to be opened or closed by a hand valve 42 of any well-known construction. Upon the top 43 of tank 38 is secured, by welding or other suitable means, a casting 44 which contains a bore 45 opening downwardly through a 10 port 46 through top 43 and into tank 38. The casting extends through wall 12 and has formed thereon a funnel-like receiver 47. A valve seat 48 (Fig. 4) is provided adjacent the port 46 adapted to be closed by a milled valve member 15 49 which is operated by a screw-threaded valve stem 50 extending outside of the wall 12. An ordinary water gauge 51 is provided outside of the wall 12 and has connection with the tank 38 near its top and bottom, respectively. By 20 these means, when it is desired to refill the tank, as indicated by gauge 51, valve 42 is closed. Valve 49, 50 is opened and water is run in to funnel receiver 47 preferably from a hose extended from an adjacent faucet. When the 25 tank is filled valve 49, 50 is closed and valve 42 opened, whereupon water may be supplied from the tank to the well 25 as fast as air is admitted to the interior of said tank.

To provide for admitting this air rapidly, and 30 without noise, I arrange a tube 52 of small bore alongside of the inner side wall of tank 38 and carry said tube over and through top wall 43, as indicated at 53 in Figs. 3 and 5. The tube discharges upon a plate receiver 54 35 spaced as indicated at 55 (Fig. 5) from the top 43. As indicated in dotted lines in Fig. 3, the plate 54 may extend across an inside upper corner of tank 38, and the depending nozzle 53 is substantially in contact with the plate 54 40 which is provided with a multiplicity of apertures 56 next to the two walls of the corner 57 of the tank where the plate 54 is located. The lower end 58 of tube 52 extends to the water-line 41 in reservoir 25, as shown in Fig. 11. 45 When from use of water the line drops below the end 58, air will be forced through tube 52, pushing the small column of water in said tube ahead of it, which will be discharged against the plate 54 at the corner 57 of tank 38 and run 50 noiselessly down the walls of said tank the column of water will extend in tube 52 to the level of the water in tank 38 by reason of the pressure of air upon the surface 41 of water in sump 16 and its tendency to form vacuum at the top of 55 the tank communicated to the tube 52 by reason of its sealed connection with the top of the tank. The air supplied through tube 52 will escape through opening 55. Water will flow from the tank into reservoir 25 until the waterline 41 60 is brought above the end of tube 58. In this way water will be supplied as required from the tank 38 without any noise of bubbling or dripping, or, in fact, any noise whatever.

Upon a suitable shelf support 59 in a chamber 65 60 in the upper part of the cabinet is located a blower 61 and a compressor pump 62. A motor 63 operates the blower and compressor at relatively slow speeds by means of pulleys 64 on the motor and belt-connected pulleys 65 and 66 70 on the blower and the pump, respectively. In the form of Fig. 1, the air is drawn from the room through a grill 67 and the blower discharges through a partition 68 into passageway 28 and from thence through tortuous passageway 33 and up through the scrubber formed by a 75

multiplicity of zigzag plates 69 and through port opening 70 into the chamber 71 above the bed, as indicated in dotted lines in Fig. 6.

In the form shown in Fig. 9, the blower discharges through a conduit 72 directly into tortuous passage 34 and moves the air in the opposite direction through scrubber 69 and to the last leg of tortuous passage 34, from where it is delivered to bottom passageway 13 under sloping bottom wall 15 and above a second bottom wall 74, which is formed with a multiplicity of centrally-disposed openings 75, as clearly shown in Fig. 12. Directly below the opening 75 in wall 74 is a removable pan 76 adapted to be drawn out through an opening 77 in the 15 end of the cabinet normally closed by a door 78. The passageway 79 between the pan 76 and the bottom partition 74 communicates with the room through a multiplicity of ornamental openings 80, 81 in the two side walls 13 and 14, as shown 20 in Figs. 9 and 10, whereby the conditioned, cooled air will be blown from the cabinet in a distributed manner close to the floor.

The pump 62 has its inlet pipe 82 dip into the water of well 25 within a strainer member provided with a removable cover 83. The water in the reservoir 25 may be drained therefrom by means of cock 84, and access to the reservoir 25 is had through door 85 hinged to end wall 12, as shown in Fig. 9, by which means the 30 accumulated dirt in reservoir 25 may be removed and fresh strainer cloths put in position about the water inlet pipe 82. From the pump 62 the outlet pipe 82' extends through the upper parts of tortuous chamber 33 or 34, as shown 35 in Figs. 1 and 9, and is formed with spray nozzles 86 adapted to deliver a fine spray, and spray nozzles 87 adapted to deliver a coarse spray, there being one of each type of nozzle over each of the legs (except the two air-delivery 40 end ones of both of the forms shown in Fig. 1 and also in Fig. 9). In the form of Fig. 9, the first two of the legs of tortuous passageway 34 are reached by branch pipes 88 and 89 respectively.

As shown, particularly in Figs. 1 and 7, in the form shown in Fig. 1, I mount the spray pipe 90 (a continuation of delivery pipe 82') upon a plate 91 adapted to be bolted into a recess 92 on the back of the cabinet. A union 50 nut 93 connects the pipe 82' with the spray pipe 90, and by loosening up the union nut through door 94 on top of the cabinet and taking out screws 95 by means of which the plate 91 is secured in position, the spray pipe may be 55 withdrawn for cleaning. In a similar manner, the main part of the spray pipe 96 may be withdrawn from the form of cabinet shown in Fig. 9 through the top of said cabinet.

As shown in Figs. 6 and 7, the form of cabinet 60 of Fig. 1 is adapted to be used directly with a bed and the mattress thereof as a bed air-conditioner. In this form, legs 97 give a lateral support for top wall 98, end walls 99 and 100 and a front wall 101 which supports a pair of doors 65 102, 103, as shown in Fig. 6, which are adapted to swing outwardly to admit to the inside of the chamber for making the bed and for getting into the bed, and which are closed at night upon the sleeper by means of latches 104 and 105. 70 The several walls carry flaps 106 of air-impermeable material which underlie the mattress 107, by means of which an enclosed chamber 108 is formed, which chamber is, however, open at 109 above the head of the sleeper for the 75

full width of the bed for a substantial width of opening, of say sixteen or eighteen inches. From said opening the top wall slopes downwardly as indicated at 110 and carries a flexible cloth partition 111 immediately adjacent the air inlet aperture 70, so that the cold conditioned air coming in must flow through the mattress-wide opening 112 below the flexible partition 111 adjacent the bed and the warmer air will be pushed and gravitated out through opening 109. A switch 113 close to the head of the sleeper is adapted to turn the motor 63 on or off. A second switch 114 through suitable connections will connect or disconnect the compressor, which is also controlled by automatic thermostatic means of well-known construction to prevent the temperature within the chamber 115 of the casting member 22 from going below a predetermined point. This chamber is filled with some suitable conducting fluid sealed within the chamber, which includes a multiplicity of coils 116 of tubing carrying refrigerating fluid from compressor 20, by means of which the casting 17 and fin plates 23 are suitably cooled. Within the final scrubber leg passage of the tortuous passage 33 of the construction of Fig. 1, and just below air-discharge opening 70, is located an electric heater 117, which is automatically controlled by a thermostat 118 of well-known construction indicated diagrammatically in Fig. 6, which heater will be automatically put in operation whenever the temperature within the chamber 71 falls below a predetermined point.

It will be understood that in the form of Fig. 1 it will frequently be unnecessary to employ the refrigerating member 17, as sufficient reduction of temperature will be produced by the spray alone. Further, when the device is used in cool weather or in winter weather, and the conditioning of the air by removal of dust and germs through the spray is desirable but too much cooling might result, the electric heater will sufficiently temper the otherwise conditioned air.

The operation and advantages of my invention as above set forth are effective and highly advantageous.

The difficulty in economically cooling air comes from the fact that heat exchange surfaces for that purpose must be at a temperature materially higher than freezing point, as otherwise they would simply frost over and no lower temperature could be obtained anyway. Practical working heat exchange temperatures cannot be much below 40° F. That means that the difference in temperature between the air to be cooled (between 70 and 80° in a properly conditioned room) and the heat exchange surface is not great. Consequently, a very large amount of heat exchange surface is necessary in order to cool any considerable amount of air, sharply distinguished from heat-conditioning, where the difference in temperature between the heat exchange surface and the air is ordinarily several hundred degrees.

Mechanical means for obtaining the large heat exchange surface necessary has proved expensive and has required, for cabinet air-conditioners, an extremely bulky and cumbersome cabinet. In the present invention this is obviated by the simple and efficient expedient of making a spray of water in the elongated, tortuous air passageway furnish the heat exchange surface. Such a spray, with literally millions of tiny globules of water having their surface ex-

posed to the currents or air, produces an enormous aggregate surface. And in applicant's invention the water is simply and efficiently cooled by reason of the fact that the spray films over a refrigerating heat exchange member and yields its heat taken from the air to that member before returning to the water reservoir, cooled to approximately the temperature at which the refrigerating member is maintained, which may be around 40° F. Furthermore, in the form of the device shown in Figure 9, the cooled air passes under the sloping drain board, so that whatever loss of heat there may be from the water after it has been cooled by the refrigerating member will go to the air, which will be delivered at the floor level, where it should be, preventing unpleasant currents and drafts and causing the cooled air to mix gradually with the warmer air and progressively build up an area of cooled air from the floor toward the ceiling.

In the form of the device shown in Fig. 1, which is adapted to be employed in connection with a bed air-conditioner, such as shown in my aforesaid co-pending application, the refrigerating member is supplemental and will not need to be employed except on days when the air is abnormally humid. On other days the latent heat of evaporation will sufficiently cool the air, and, as heretofore pointed out, under such circumstances, when the bed air-conditioner is used throughout the year, and in cool weather, there may be too great cooling of the air, in which case the electric heater and thermostat will sufficiently temper the air to maintain a desired temperature and at the same time get the benefits of washing and freeing the air from dust and germs, which comprises an important feature of the invention.

I claim:

1. An air-conditioner comprising a cabinet embodying a plurality of vertical partitions, forming a series of connected up and down passageways which in their entirety make an elongated tortuous passageway, means to move air through said passageway and discharge it from the cabinet, means in the cabinet to circulate water therein and form a spray descending from the top to the bottom of the several vertical portions of said passageway, and a refrigerating member extending along the bottoms of said portions, said refrigerating member comprising a cast metal body with the tubes for conveying refrigerating fluid entirely sealed within said body.

2. An air-conditioner comprising a cabinet embodying a plurality of vertical partitions, forming a series of connected up and down passageways which in their entirety make an elongated tortuous passageway, means to move air through said passageway and discharge it from the cabinet, means in the cabinet to circulate water therein and form a spray descending from the top to the bottom of the several vertical portions of said passageway, and a refrigerating member extending along the bottoms of said portions, said refrigerating member comprising a hollow cast body with a multiplicity of surrounding fins and having the tubes for carrying the refrigerating fluid sealed within the chamber in said body.

3. In an air-conditioner embodying a cabinet and means for forming a water spray within the cabinet including a pump and a reservoir, a tank for supplying water to the reservoir having a

40

45

50

55

55

60

65

70

75

discharge nozzle dipping substantially below the waterline therein, and a tube having its lower end within the reservoir at said waterline and its upper end discharging into the tank to admit 5 air into the tank and permit water to flow therefrom into the reservoir when said waterline drops below the lower end of the tube.

4. In an air-conditioner embodying a cabinet and means for forming a water spray within 10 the cabinet including a pump and a reservoir, a tank for supplying water to the reservoir having a discharge nozzle dipping substantially below the waterline therein, and a tube outside of the tank and independent of the nozzle having its 15 lower end at said waterline and its upper end projected into the tank at the top thereof for admitting air into the tank and permitting water to flow therefrom into the reservoir when said waterline drops below the lower end of the 20 tube.

5. In an air-conditioner embodying a cabinet and means for forming a water spray within 25 the cabinet including a pump and a reservoir, a tank for supplying water to the reservoir having a discharge nozzle dipping substantially below the waterline therein, a tube having its lower end at said waterline and its upper end discharging downwardly within said tank, and a 30 plate at the discharge end of said tube for directing the water therefrom against a wall of the tank whereby when said waterline falls below the lower end of the tube air will be admitted noiselessly into the upper part of the tank whenever the said waterline falls below the 35 lower end of the tube.

6. In an air-conditioner embodying a cabinet and means for forming a water spray within 40 the cabinet including a pump and a reservoir, a tank for supplying water to the reservoir having a discharge nozzle dipping substantially below the waterline therein, a tube outside and adjacent a corner of said tank having its lower 45 end at the waterline of said reservoir and entering the tank downwardly at the top, and a plate angularly disposed across an upper corner of the tank and spaced from the top and positioned at the discharge end of said tube, said plate having openings adjacent the walls of the tank to permit water forced from the tube to move noiselessly down said walls.

50 7. An air-conditioner comprising a casing formed with a multiplicity of vertical passages opening successively at top and bottom into each other to form a continuous connected passageway, means to move air into said passageway at one end and discharge it from the other, a pump and pipe system wholly within the casing to spray water into the top of each vertical passageway, said pump located at one end of the casing, a sloping floor to the casing under all 55 said passages to collect the unevaporated portions of said spray for return to the pump, and a refrigerating cooling member formed with a multiplicity of fin members resting upon said sloping floor, all said fin members being formed with a cutaway portion adjacent the floor to 60 provide a continuous channel for the water being collected to flow along.

8. An air-conditioner comprising a cabinet 65 forming a chamber and having a sloping floor and formed with a sump of relatively small volume below the lower end of said floor, a series of connected vertical passages each having as its bottom a portion of said floor, a pumping system wholly within the casing for 70 forming a spray of water in the tops of each

of said passages, thence to gravitate to the floor and be conveyed thereby to the sump, means for supplying water to said sump and for controlling such supply so that when the pumping system is in operation the sump will have the 5 water level therein maintained below the discharge end of said sloping floor, and means for moving air through said passages.

9. An air-conditioner comprising a cabinet forming a chamber and having a sloping floor 10 and formed with a sump of relatively small volume below the lower end of said floor, an elongated passageway having as its bottom a portion of said floor, a unitary refrigerating member extending along the bottom of said 15 passageway close to said floor, a pumping system wholly within the casing for forming a spray of water in the upper parts of said passageway and above said member, to gravitate to and over the refrigerating member and to 20 the floor and be conveyed thereby to the sump, means for supplying water to said sump and for controlling such supply so that when the pumping system is in operation the sump will have the water level therein maintained below the 25 discharge end of said sloping floor, and means for moving air through said passageway.

10. An air-conditioner comprising a cabinet forming a chamber and having a sloping floor and formed with a sump of relatively small volume 30 below the lower end of said floor, an elongated passageway having as its bottom a portion of said floor, a refrigerating member extending along the bottom of said passageway close to said floor and comprising a cast body forming 35 a unitary chamber and a multiplicity of fins extending outwardly therefrom and above said sloping floor, a pumping system wholly within the casing for forming a spray of water in the upper parts of said passageway and above said member to gravitate to and over the refrigerating member to the floor and be conveyed thereby to the sump, means for supplying water to said 40 sump and for controlling such supply so that when the pumping system is in operation the sump will have the water level therein maintained below the discharge end of said sloping floor, and means for moving air through said 45 passageway.

11. An air-conditioner comprising a cabinet 50 forming a chamber and having a sloping floor, an elongated passageway having as its bottom a portion of said floor, a unitary refrigerator member extending along the bottom of said passageway close to said floor and comprising a cast body forming a unitary chamber and a multiplicity of fins extending outwardly therefrom and above said sloping floor, means for forming a spray of water in the upper parts of said passageway and above said member, to 55 gravitate to and over said refrigerating member and to the sloping floor, a heat-conveying liquid and an extended length of tubing in said liquid sealed within the chamber of the refrigerating member, a compressor having inlet and outlet connection with said tubing for supplying refrigerating fluid thereto, and means for moving air through said passageway.

12. An air-conditioner comprising a cabinet 60 with a floor wall, an elongated passageway 70 therein having as its bottom a continuous sloping floor spaced from the floor of the cabinet, means for delivering a spray of water in the upper parts of said passageway to gravitate to said sloping floor and be discharged therefrom 75

into a collecting sump, means close to said floor for cooling said water, a passageway at the rear of said first-named passageway communicating with the space under the sloping floor, means for causing air to enter the cabinet at its top and to move through said first-named passageway from the front to said rear passageway and into the space below the sloping floor, and a series of openings from said space for distributing said air along the floor of the room.

13. An air-conditioner comprising a cabinet with a floor wall, an elongated passageway therein having as its bottom a continuous sloping floor spaced from the floor of the cabinet, means for delivering a spray of water in the upper parts of said passageway to gravitate to said sloping floor and be discharged therefrom into a collecting sump, means close to said floor for cooling said water, a passageway at the rear of said first-named passageway communicating with the space under the sloping floor, means for causing air to enter the cabinet at its top and to move through said first-named passageway from the front to said rear passageway and into the space below the sloping floor,

a partition below said space and above the floor of the cabinet formed with a series of openings downwardly through its center, and sets of openings formed in the sides of the cabinet below said partition for distributing the air laterally in both directions from the cabinet. 5

14. An air-conditioner comprising a cabinet inclosing an elongated, relatively narrow and high spray chamber occupying part of the space within said cabinet and formed with a bottom wall, means in the cabinet to move air to and through said chamber and thereafter to discharge it from the cabinet, means in the cabinet to circulate water therein and form a spray filling said spray chamber and descending to the bottom thereof, and a refrigerating member extending along the length of said bottom wall and adapted to be engaged by and to cool substantially all of said water so circulated, said refrigerating member comprising a hollow cast 20 body with a multiplicity of surrounding fins resting upon said bottom wall and having means forming a continuous passageway for carrying the refrigerating fluid sealed within the chamber in said body. 25

FRANK A. WHITELEY.
